(57) **CLAIM**

The ornamental design for an adjustable pelvic compression belt, as shown and described.

DESCRIPTION

FIG. 1 is a perspective view of an adjustable pelvic compression belt showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

In the Figures, the adjustable pelvic compression belt is illustrated in a closed configuration as if secured around a person. It is also contemplated that the adjustable pelvic compression belt is flexible.

It is understood that the broken lines in FIGS. 1-7 indicate a stitching pattern, the ornamental aspects of which form part of the claimed design.
